Carl Edward Swanson, Chicago, Ill.

Application August 16, 1946, Serial No. 132,583

Term of patent 3½ years

(Cl. D26—13)

To all whom it may concern:

Be it known that I, Carl Edward Swanson, a citizen of the United States and resident of the city of Chicago, in the county of Cook and State of Illinois, have invented a new, original, and ornamental Design for a Lighting Device for Locks or the like, of which the following is the specification, reference being had to the accompanying drawings, forming a part thereof.

On the drawings:

Fig. 1 is a front elevation of my novel lighting device for locks or the like showing my new design.

Fig. 2 is a side elevational view thereof.

Fig. 3 is a perspective view thereof.

Fig. 4 is a top plan view thereof.

I claim:

The ornamental design for a lighting device for locks or the like, substantially as shown.

CARL EDWARD SWANSON.
